FREDERICK K. LEWIS, OF ASHTABULA, OHIO, ASSIGNOR TO THE ASHTABULA BOW SOCKET COMPANY, OF ASHTABULA, OHIO, A CORPORATION OF OHIO.

TOP FOR VEHICLES AND THE LIKE.

1,353,129.

Specification of Letters Patent. Patented Sept. 14, 1920.

Application filed October 1, 1918. Serial No. 256,442.

To all whom it may concern:

Be it known that I, FREDERICK K. LEWIS, a citizen of the United States, and a resident of Ashtabula, county of Ashtabula, and 5 State of Ohio, have invented a new and useful Improvement in Tops for Vehicles and the like, of which the following is a specification, the principle of the invention being herein explained and the best mode 10 in which I have contemplated applying that principle, so as to distinguish it from other inventions.

In most tops of the so-called "one man" type, such as are now used extensively on 15 automobiles, the extreme forward or "outrigger" bow, as it is called, is carried by means of swinging arms pivotally attached to the main bow at some distance from the point of pivotal attachment of the latter to 20 the vehicle body, so that such arms, with such outrigger bow extending substantially horizontally in the open position of the top, together constitute what may be termed an articulated outrigger bow. To each of these 25 arms, or the rear portions of such articulated outrigger bow, there is in turn usually attached an intermediate or supplemental bow, the function of which is to support the stretch of cover material between the main 30 bow and the outrigger bow proper. One of the problems in the construction of tops of this sort is to so interconnect the three bows in question that such supplemental bow will be held in proper position in the open condition 35 of the top under the cover load, as well as be folded in unison with the main and outrigger bows, when the top is being closed. The object of the present invention accordingly is to provide, by means of a novel arrangement of links, for the support and 40 operation of such supplemental bow, as well as at the same time to assist in supporting the outrigger bow. A further object is to provide means of this sort which may be 45 readily constructed and assembled, allowing for a certain desirable latitude in the adjustment of the position of the supplemental bow.

With the foregoing and related ends in 50 view, the invention, then, consists of the means hereinafter fully described and particularly pointed out in the claims, the annexed drawing and the following description setting forth in detail certain mecha-

nism embodying the invention, such disclosed 55 means constituting, however, but several of the various mechanical forms in which the principle of the invention may be used.

In said annexed drawing:—

Figure 1 is a side elevational view of a 60 top supporting structure embodying my present improvements, such top being shown as mounted on an automobile body of conventional form; Fig. 2 is a side elevational view on a larger scale of the upper portion 65 of the main bow and of the attached supplemental and outrigger bows, showing the means operatively connecting the same together, which are of present interest; Fig. 3 is a view similar to that of Fig. 2, but showing 70 a modified construction of the means thus connecting the main, supplemental and outrigger bows; Fig. 4 is a view similar to Fig. 2, but showing still another modified form of construction; and Fig. 4^a illustrates a detail in the latter.

It is of course a matter of indifference whether the top is used on an automobile, motorboat or otherwise, and, depending upon its longitudinal extent, a smaller or 80 larger number of bows, in addition to the outrigger structure of present interest, may be utilized; thus in the construction illustrated in Fig. 1, in addition to the forwardly inclined main bow 1 pivotally attached to the body 2 of the vehicle adjacent the rear seat of the latter, I show a rear main bow 3 that is preferably pivotally attached to such forward main bow near its lower end, as well as a supplemental bow 4 85 shown as attached to said main bow 1 approximately midway between its ends. It will be understood that in certain cases it may be more convenient to attach this intermediate bow to the rear main bow 3. It 90 will be also understood that the term "bow" is used herein inclusively to designate not merely the wooden bow proper, but also the metallic sockets carrying the same, these parts when regarded in side elevation constituting the equivalent of the so-called "sticks" as they are called in the old wood construction. It is accordingly a matter of convenience to refer to the parts in the singular, as though the structure lay all in a 105 single vertical plane, since the parts of interest do actually lie in such a plane.

As already indicated, the portion of the

structure of present interest is the forwardly extending frame, whereby a corresponding portion of the top covering 5, which projects over the front seat, is supported. This structure, as likewise already indicated, comprises an articulated auxiliary bow, or, as I prefer to call it, outrigger bow 6, the latter term referring more particularly to the outer portion or bow 7 proper, which is secured to the forward main bow 2 by means of an arm 8 (one on each side of course) pivotally attached to said main bow and to the rear ends of such outrigger bow, and so constituting the inner portion of said articulated auxiliary bow 6. The point of attachment of this arm to the main bow is preferably in line with or just above the side edge of the cover, so as to be hidden by the latter, and the joint 9 between said arm and the outrigger bow is a rule joint disposed so as to prevent further bending of the arm in question, when extended in horizontal fashion, as in the open condition of the top.

Pivottally attached to the arm 8 is a supplemental bow 10, that in such open condition of the top is designed to extend forwardly at an angle with respect to said arm, so as to support the cover at a point approximately midway between the main bow 1 and outrigger bow 7. The means for operatively connecting this supplemental bow with said main and outrigger bows may take on various modified forms, all coming within the broader aspect of the present invention, as illustrated in detail in Figs. 2, 3 and 4 respectively. All these forms are similar, in that such connecting means comprise a three-part articulated link or brace, the intermediate link 11 being pivotally attached to said supplemental bow, and the free ends of the two other links 12 and 13 being respectively attached to the main bow at a point above the point of pivotal attachment of the arm 8 thereto, and to the outrigger bow at a point beyond the joint 9 between the latter and said arm. All of the joints except as hereinafter indicated are freely bending, both those between the links themselves and those between the two longer links and the main and outrigger bows respectively, so that the intermediate link which is preferably considerably shorter than the two other links, operates in effect as a double-arm lever or equalizer bar, as will be presently more specifically set forth.

In the construction shown in Fig. 1, the intermediate link or equalizer bar is a straight member and lies substantially in line with the two other links in the extended condition of the top as shown in Fig. 1, although it has been found preferable, as better illustrated in Fig. 2, to drop the pivotal connection between this intermediate

link and the forward longer link a trifle below the line connecting the point of attachment of such last named link with the outrigger bow, and the point of attachment of the rear link with the main bow. The effect of dropping the pivotal connection just referred to apparently is to render the structure more fully self-sustaining in such extended condition of the top, this effect being further augmented by disposing such forward link and its connections so that said link, in the same condition of parts, lies slightly below the joint that connects the outrigger bow with the swinging side arm.

Instead of the intermediate link being a straight member, as illustrated in Figs. 1 and 2, it may be in the form of a bell-crank 14, as shown in Fig. 3. There is some advantage in this form over the other in certain classes, or rather sizes, of tops, enabling, as it does, connection between the system of links and the intermediate bow to be dropped that much lower without altering the alinement of the links as a whole, or shifting the points of attachment of the two longer links to the outrigger bow and main bow respectively.

In Fig. 4, I show still another form of intermediate link 15, in which the one arm thereof, namely, the rear arm, is longer than the other. This permits the point of attachment of the longer link 16 to be shifted to the rear a corresponding amount on the main bow, without necessitating a change in the length of such link. In other words, the point of attachment in question, instead of being in front of the main bow directly over the point of attachment of the corresponding side arm, may be on the side or lateral face of the main bow, where the inclination of the latter remains unchanged, or as shown in Fig. 4, said main bow may be inclined rearwardly instead of forwardly without projecting the point of attachment of the link thereto any farther in front of said main bow than before. In this construction the forward long link 17, instead of being straight has its ends respectively bent downwardly, thereby permitting it to fold more compactly alongside link 16, when the top is collapsed.

In each of the foregoing constructions, I find it desirable to utilize a stop, such as a lug 18 on arm 8, just forwardly of the pivotal connection of supplemental bow 10 with said arm, whereby the position of said bow is determined when the top is extended. A stop 19 (see Figs. 4 and 4^a) between the equalizer member and one of the long links 125 may also be employed if desired.

The mode of operation of my improved top is sufficiently illustrated by the showing in Fig. 1 in connection with the first form, where the latter is illustrated in folded posi-

tion in dotted outline. Thus, by pulling down on the joint 9 between the side arm 8 and outrigger bow 7, such joint will obviously be broken, and as the side arm drops into parallel relation with the main bow 1, the interconnected links cause the outrigger bow to fold up against such side arm and into similar parallel relation with the main bow. Simultaneously of course the supplemental bow 10 is folded in between said outrigger bow and main bow, its movement occurring in unison with that of the outrigger bow, so that the portions of the cover material 5 between it and said outrigger bow and main bow, respectively, will be given an opportunity to drop into neat folds between such bows.

As the folding operation proceeds, the intermediate link 11, which is free to swing about its connection with said supplemental bow, will gradually assume the position shown in dotted outline or a position approximating the one thus illustrated, a characteristic of this member being that its final position in the folded condition of the top may vary within certain limits without affecting in the slightest such folding operation or the compactness of the parts in their collapsed condition. In other words, in assembling my present improved top, the links in question, after being previously connected together, may be riveted or bolted to the bows disposed in proper extended position, holes being previously drilled for the purpose, no fitting or trying being necessary in order to insure the proper correlation of links and bows in the folding operation. The intermediate link or equalizer bar, it will be seen, operates to automatically take care of any slight inaccuracies in the bow assembly, as well as any slight displacement of the bows such as is apt to occur incidentally to the attaching of the cover material thereto. A great deal of difficulty has been experienced in this latter connection with the various types of one man top at present on the market, in that the trimmer, in order to properly tension the top covering, is apt to place the one side of the supporting framework under a greater strain than the other, with the result that binding inevitably occurs when the structure is folded or collapsed. However, the intermediate link or equalizer bar of the present construction has been found to act freely under all conditions, and imparts a desirable degree of flexibility to the structure.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a top for vehicles and the like, the combination of a main bow; a two-part articulated outrigger bow having its rear portion pivotally connected to said main bow; a supplemental bow pivotally connected to such rear portion of said outrigger bow; and three links directly pivotally connected together, the intermediate link being pivotally attached to said supplemental bow and the other two links being respectively pivotally attached to said main bow and to said outrigger bow beyond the joint therein. 75

2. In a top for vehicles and the like, the combination of a main bow; a two-part articulated outrigger bow having its rear portion pivotally connected to said main bow; a supplemental bow pivotally connected to such rear portion of said outrigger bow; 85 and three links directly pivotally connected together, the intermediate link being shorter than the other two and pivotally attached at its midpoint to said supplemental bow and such other links being respectively pivotally attached at their outer ends to said main bow and to said outrigger bow beyond the joint therein.

3. In a top for vehicles and the like, the combination of a main bow; a two-part articulated 95 outrigger bow having its rear portion pivotally connected to said main bow; a supplemental bow pivotally connected to such rear portion of said outrigger bow; three links directly pivotally connected together, the intermediate link being pivotally attached to said supplemental bow and the other two links being respectively pivotally attached to said main bow and to said outrigger bow beyond the joint therein; and a stop adapted 100 to determine the position of said supplemental bow when the top is extended.

4. In a top for vehicles and the like, the combination of a main bow; a two-part articulated outrigger bow having its rear 110 portion pivotally connected to said main bow; a supplemental bow pivotally connected to such rear portion of said outrigger bow; three links directly pivotally connected together, the intermediate link being pivotally attached to said supplemental bow and the other two links being respectively pivotally attached to said main bow and to said outrigger bow beyond the joint 115 therein; and a stop on such rear portion of 120 said outrigger bow adapted to engage with said supplemental bow and determine its position when the top is extended.

5. In a top for vehicles and the like, the combination of a main bow; a two-part 125 articulated outrigger bow having its rear portion pivotally connected to said main bow; a supplemental bow pivotally connected to such rear portion of said outrigger bow; and three links directly pivotally con- 130

- nected together; the intermediate link being pivotally attached to said supplemental bow and the other two links being respectively pivotally attached to said main bow and 5 to said outrigger bow beyond the joint therein, the point of connection between the forward and intermediate links lying below a line through the points of connection of said forward link and said outrigger bow and 10 between the rear link and said main bow when the top is extended.
6. In a top for vehicles and the like, the combination of a main bow; a two-part articulated outrigger bow having its rear 15 portion pivotally connected to said main bow; a supplemental bow pivotally connected to such rear portion of said outrigger bow; and three links directly pivotally connected together, the intermediate link being 20 in the form of a bell-crank pivotally attached to said supplemental bow and such other links being respectively pivotally attached to said main bow and to said outrigger bow beyond the joint therein.
7. In a top for vehicles and the like, the combination of a main bow; a two-part articulated outrigger bow having its rear portion pivotally connected to said main bow; a supplemental bow pivotally connected to such rear portion of said outrigger bow; a member pivotally attached to said 30 supplemental bow and serving as an equalizer; and rigid members flexibly connecting said member with said main bow and with said outrigger bow beyond the joint therein, respectively. 35
8. In a top for vehicles and the like, the combination of a main bow; a two-part articulated outrigger bow having its rear portion pivotally connected to said main bow; a supplemental bow pivotally connected to such rear portion of said outrigger bow; a member in the form of a bell-crank pivotally attached to said supplemental bow and serving as an equalizer; and members 40 flexibly connecting the arms of said member with said main bow and with said outrigger bow beyond the joint therein, respectively. 45
9. In a top for vehicles and the like, the combination of a main bow; a two-part articulated outrigger bow having its rear portion pivotally connected to said main bow; a supplemental bow pivotally connected to such rear portion of said outrigger bow; a member in the form of a bell-crank pivotally attached to said supplemental bow and serving as an equalizer; and links flexibly connecting the arms of said member with said main bow and with said outrigger bow beyond the joint therein, respectively. 50 55
- Signed by me, this 28 day of September, 1918.

FREDERICK K. LEWIS.
